UNITED STATES PATENT OFFICE

ROLLAND E. PETERSON, OF GARY, INDIANA

OPENER FOR METAL PACKS

Application filed April 17, 1928. Serial No. 270,735.

This invention relates to mechanism for opening metal packs, and it has for its primary object to provide an apparatus for effecting separation of the sheets of rolled metal packs.

A further object is to provide a simple and effective apparatus by means of which the sheets of a rolled metal pack may individually and in rapid succession be stripped from 10 adhering relation to one another.

With these and other objects in view, the invention resides in the features of construction, arrangement of parts and combinations of elements which will hereinafter be fully 15 described, reference being had to the accompanying drawings, in which—

Figure 1 is a view of the invention partly in longitudinal section and partly in side elevation; and

Figures 2 and 3 are cross sections of the same taken, respectively, substantially on lines 2—2 and 3—3, Fig. 1.

Referring to said drawings, 1 designates a table upon which are mounted in suitably 25 spaced relation a succession of pairs of pinch rolls by means of which packs of rolled metal sheets are advanced over said table. Located in advance of the entering pair 2 of pinch rolls is a vertically movable power hammer, 30 or break down, by means of which the forward edges of the sheets of the pack, preferably throughout a length of approximately three inches, are broken down for effecting at and adjacent to said edges an initial separation thereof, and also by means of which said 35 broken down edges are instantly re-bent, or returned to the original plane thereof.

In the illustrative construction shown, the breakdown comprises a hammer 3 carried by a 40 piston rod 4 adapted to be actuated by air or other pressure admitted to a power cylinder 5. Said hammer has a transverse length exceeding the width of the packs which are to be opened and has therein a slot 3^a through 45 which the packs are advanced. In actuation, said hammer travels throughout one complete cycle; that is to say, the hammer is actuated to move downward for the required distance for effecting breaking down of the edge 50 of the pack and then initially to return for

restoring the broken-down edge to the original plane.

The power for actuating the hammer is applied automatically in any practical manner, as by operation of a valve of the power cylinder effected automatically through shifting of a limit switch 6 located in an electrical control circuit (not shown) for such valve, said switch being so located that shifting thereof is effected by the advancing pack at 55 any appropriate point in the travel of the latter.

Following the return of the broken down edge of the pack to the original plane, as aforesaid, the pack is advanced through the 60 pinch rolls 11 to a position wherein its forward end overlies a magnet 7 and also underlies a vacuum cup 8, at which position said vacuum cup is actuated to seat firmly upon the top of the forward edge portion of the 70 topmost sheet of the pack and then to move to an elevated position for lifting said forward edge portion of said sheet.

The advance of the pack is then continued to direct said topmost sheet over, and the remainder of the pack under, or beneath, a transversely disposed stationary blade 9 whereby the splitting of said topmost sheet from the pack is effected. Such advance carries the forward end of said topmost sheet 75 to a suitably located elevated pair of pinch rolls 10 by which it is seized, and at the same time enters the remainder of the sheets of the pack in a pair of pinch rolls 11'. The said pairs of rolls 10 and 11' cooperate to draw 80 the pack forward and in the advance movement of the latter the blade 9, which presents a knife-like edge, acts to sever or split the topmost sheet from the next adjacent sheet of the pack.

From the rolls 10 the separated sheet is advanced to a suitable conveyor 12 whereby it may be carried to any suitable delivery point.

The vacuum cup 8, as herein shown, is carried by a piston rod which is reciprocable by and relative to a power cylinder 13 of a type similar to the cylinder 5 hereinbefore referred to, but in which a desired interval of time is permitted to elapse between the seating and return movements of the cup, the pur-

pose being to permit the cup to retain its lifting grip upon the engaged sheet until the latter has passed to a position in which its upper edge overlies the blade 9. The cylinder 13 is mounted pivotally to allow the swinging movement thereof required during the interval in which the cup 8 retains its hold upon the sheet.

The actuation of the cup 8, as aforesaid, 10 is effected by any appropriate means, as through the intermediacy of a limit switch 14 which is so positioned that it is shifted by contact therewith of the forward edge of the advancing pack at the proper instant, said 15 switch being located in an electrical circuit (not shown) which, when closed by such shifting of said limit switch, effects admission to the cylinder of the actuating fluid. Inasmuch as power cylinders of the character 20 referred to operated through the closing and opening of electric control circuits are well known in the art, and since the details of structure of such cylinders and of their circuit connections form no part of this invention, such details are omitted from this disclosure.

The magnet 7 may be permanently energized or it may be energized only during the 30 interval during which the vacuum cup functions to elevate and support the topmost sheet. So energized, it attracts and holds down the forward end of the pack with sufficient force to prevent elevation of other than the topmost sheet. As is manifest, the force 35 exerted by said magnet supplements the force of gravity acting upon the forward end of the pack, and the magnetic force exerted upon the sheets of the pack progressively decreases from the lowermost of the uppermost sheet, 40 so that the resistance offered to elevation of the said topmost sheet may more or less readily be overcome by the lifting force exerted by the vacuum cup.

The sheets remaining in the pack following 45 passage through the pinch rolls 11' act to shift a limit switch 14' for effecting actuation of a second vacuum cup 8' which overhangs a second holding magnet 7' just prior to the time that the foremost edge of the pack 50 reaches the position of a second sheet stripping blade 9', and which acts to elevate the topmost sheet and direct the same to a second pair of elevated pinch rolls 10' while the remaining sheets of the pack are advanced beneath said blade to a set of pinch rolls 11".

Additional vacuum cups 8", limit switches 14", magnets 7", blades 9" and rolls 10" are provided in succession and in such number 60 that all of the various sheets composing the pack are successively separated in the manner hereinbefore described.

Should any of the successive vacuum cups 65 fail to exert the force required to elevate the forward end of the topmost sheet, as described, the pack will obviously be advanced

to the next, whereby it may function. In such case, the separation of the sheets may be effected; but, should none of the cups so function, the entire pack will pass through the machine without injury either to the latter or to the pack.

While I have herein specifically described one form which my invention may assume in practice, it will be understood that this form of the same is shown for purposes of illustration and that the invention may be modified and embodied in various other forms without departing from its spirit or the scope of the appended claims.

What is claimed is—

1. A machine for separating the sheets of metal packs, comprising an aligned succession of relatively spaced pairs of pack-feeding pinch rolls, automatic means for preliminarily breaking down and restoring to the original plane thereof the foremost edges of the sheets of a pack, and an aligned succession of mechanisms located between the successive pinch rolls so as to receive the pack fed by the latter, each of said mechanisms including a stripping blade located above and adjacent to the path of travel of the pack, a holding magnet beneath said path of travel for supplementing the force of gravity acting upon the pack, means movable into lifting relation to the foremost edge portion of the topmost sheet of the traveling pack whereby said sheet is directed over the top of said blade, and a pair of pinch rolls located for automatically seizing said elevated edge portion of said sheet and for removing same from the remainder of the pack.

2. A machine for separating the sheets of metal packs, comprising an aligned succession of relatively spaced pairs of pack-feeding pinch rolls, automatic means for preliminarily breaking down and restoring to the original plane thereof the foremost edges of the sheets of a pack, and an aligned succession of mechanisms located between the successive pinch rolls so as to receive the pack fed by the latter, each of said mechanisms including a stripping blade located above and adjacent to the path of travel of the pack, means operable into lifting relation to the foremost edge of the topmost sheet of the advancing pack whereby said sheet is elevated and directed over the top of said blade, magnetic means located beneath the path of travel of the pack for resisting elevation of other than said topmost sheet, and automatic means for seizing and removing said sheet as the remaining sheets of the pack are advanced beneath said blade.

3. A machine for separating the sheets of metal packs, comprising an aligned succession of relatively spaced pairs of pack-feeding pinch rolls, automatic means for preliminarily breaking down and restoring to the original plane thereof the foremost edges of

the sheets of a pack, and an aligned succession of mechanisms located between the successive pinch rolls so as to receive the pack fed by the latter, each of said mechanisms including a stripping blade located above and adjacent to the path of travel of the pack, means operable into lifting relation to the foremost edge of the topmost sheet of the advancing pack whereby said sheet is elevated and directed over the top of said blade, magnetic means located beneath the path of travel of the pack for resisting elevation of other than said topmost sheet, and pinch rolls located in an elevated position for gripping and automatically removing said elevated sheet at the advancing speed of the remainder of the pack.

4. A machine for separating the sheets of metal packs, comprising an aligned succession of relatively spaced pairs of pack-feeding pinch rolls, automatic means for preliminarily breaking down and restoring to the original plane thereof the foremost edges of the sheets of a pack, and an aligned succession of mechanisms located between the successive pinch rolls so as to receive the pack fed by the latter, each of said mechanisms including a stripping blade located above and adjacent to the path of travel of the pack, means operable into lifting relation to the foremost edge of the topmost sheet of the advancing pack whereby said sheet is elevated and directed over the top of said blade, magnetic means located beneath the path of travel of the pack for resisting elevation of other than said topmost sheet, and pinch rolls located in an elevated position for gripping and automatically removing the elevated sheet at substantially the same time the remaining sheets of the pack are entered between the next pair of said succession of rolls, whereby said sheet and said pack are drawn forward on opposite sides of said blade.

5. A machine for separating the sheets of metal packs, comprising an aligned succession of relatively spaced pairs of pack-feeding pinch rolls, automatic means for preliminarily breaking down and restoring to the original plane thereof the foremost edges of the sheets of a pack, and an aligned succession of mechanisms located between the successive pinch rolls so as to receive the pack fed by the latter, each of said mechanisms including a stripping blade located above and adjacent to the path of travel of the pack, means operable into lifting relation to the foremost edge of the topmost sheet of the advancing pack whereby said sheet is elevated and directed over the top of said blade, magnetic means located beneath the path of travel of the pack for resisting elevation of other than said topmost sheet, and pinch rolls located in an elevated position for gripping and automatically removing the elevated sheet at substantially the same time the remaining sheets of the pack are entered be-

tween the next pair of said succession of rolls, whereby said sheet and said pack are drawn forward on opposite sides of said blade, and conveyors arranged to receive the stripped sheets from said elevated rolls.

6. A machine for separating the sheets of a metal pack including means formed to receive the foremost edges of sheets of the pack and to engage the top and bottom faces of the pack, means to move said first means downwardly and then upwardly into the original plane thereof so as to flex said edges of the pack throughout the width thereof thereby to effect separation of the foremost edges of the pack, a succession of mechanisms each including means to raise the foremost edge of the uppermost sheet of the pack and to hold the remainder of the pack against upward movement, automatic means having a part formed to engage beneath the said raised edge and to strip and remove said sheet from the pack, means to move the pack into engagement with said raising and holding means and to then advance said remainder of the pack, and means to advance said remainder of the pack to the succeeding mechanism.

7. A machine for separating the sheets of a metal pack including means to initially separate the foremost edges of the sheets of the pack, a succession of mechanisms each including means to raise the foremost edge of the uppermost sheet of the pack and to hold the remainder of the pack against upward movement, automatic means having a part formed to engage beneath the said raised edge and to strip and remove said sheet from the pack, means to move the pack into engagement with said raising and holding means and to then advance said remainder of the pack, and means to advance said remainder of the pack to the succeeding mechanism.

8. A machine for separating the sheets of a metal pack including means to initially separate the edges of the sheets at one end of the pack, a succession of mechanisms each including means to raise the said edges of the uppermost sheet of the pack from the remainder of the pack, automatic means to grip said edge and to remove said sheet from the remainder of the pack, and means to advance the remainder of the pack to the succeeding mechanism.

9. A machine for separating the sheets of a metal pack including means formed to receive the foremost edges of the sheets of the pack and to engage the top and bottom faces of the pack, means to move said first means downwardly and then upwardly into the original plane thereof so as to flex said edges of the pack throughout the width thereof thereby to effect separation of the foremost edges of the pack, a succession of mechanisms each including means to raise the said edge of

the uppermost sheet of the pack from the remainder thereof, automatic means to grip said edge and to remove said sheet from the remainder of the pack, and means to advance the remainder of the pack to the succeeding mechanism.

In testimony whereof, I affix my signature.
